UNITED STATES PATENT OFFICE.

EDGAR W. ADAMS, OF EAST ORANGE, NEW JERSEY, ASSIGNOR TO WESTERN ELECTRIC COMPANY, INCORPORATED, OF NEW YORK, N. Y., A CORPORATION OF NEW YORK.

SWITCHING APPARATUS.

1,309,231.

Specification of Letters Patent. Patented July 8, 1919.

Application filed February 14, 1918. Serial No. 217,173.

To all whom it may concern:

Be it known that I, EDGAR W. ADAMS, a citizen of the United States, residing at East Orange, in the county of Essex, State of New Jersey, have invented certain new and useful Improvements in Switching Apparatus, of which the following is a full, clear, concise, and exact description.

This invention relates to telephone systems wherein the operations involved in the interconnection of subscribers' lines are accomplished either entirely or in part by the use of machine switching apparatus.

More particularly, it relates to a switch for use in a system of this character which is designed to operate automatically in response to the initiation or extension of a call to effect an interconnection between a line or connecting circuit, with which such switch is associated, and any one of a plurality of other connecting circuits.

An object of the present invention consists in the provision of an automatically operated switch comprising movable contacts arranged to be driven by motive means successively into engagement with each of a series of stationary terminals or contacts; such engagement serving not only to effect electrical connection between the movable contacts and the successive connecting circuits represented by said stationary contacts, but also to mechanically control and to accurately determine the extent of operation of the movable contacts necessary to bring about the desired circuit connection.

A feature of the invention relates to the provision of means for imparting a reciprocating motion to the movable contacts, together with a novel arrangement of the stationary terminals, such that said movable contacts are permitted to escape from their engagement with one set of terminals, and, under the influence of a constantly applied source of power, are driven into engagement with the next succeeding set. In this position the movable contacts are momentarily arrested until they are again released by the operation of said reciprocating means and driven another step forward.

Such other and further objects as are contemplated by the present invention, will become apparent from a consideration of the following description.

In the drawing, Figure 1 is a side elevation, partly in section, showing one embodiment,

ment of an automatic switch constructed in accordance with the principles of this invention. This view also illustrates a convenient method of mounting a plurality of switch units upon a common shaft, which may be constantly driven to supply the necessary power for actuating the movable contacts of each of the several units; Fig. 2 is a combined plan and sectional view taken as on the line 2—2 of Fig. 1, with certain parts broken away and others omitted to give a clear illustration of the method of operation; Fig. 3 is a detail view in perspective showing a set of movable contacts, together with current-conveying wipers arranged to maintain a constant connection between said contacts and stationary parts of the switch structure; Fig. 4 is a broken vertical section of the stationary contact bank taken as along the line 4—4 of Fig. 1. This view best discloses the manner in which the stationary contacts are vertically and successively staggered to enable an escapement action by a reciprocating motion of the movable contacts from one set of stationary contacts to the next; and Fig. 5 is a diagrammatic showing of a circuit arrangement illustrating one application of the switch to a telephone system.

Considering the drawings particularly, there is shown at 1 a mounting plate upon which the parts of the switch structure are assembled. At one end, the plate 1 is circular in form and is fashioned to give a plurality of annular supporting surfaces or tables 2, 3 and 4. Mounted upon the outermost of these supporting surfaces 2 is a cylindrical contact bank 5. The contact bank 5 is comprised of circular layers of insulating material 6 and contacts 7, 8. The contacts 7, 8, which are securely held between insulating layers 6, are arranged in sets of three each, the contacts of each set being in vertical alinement with each other, and projecting inwardly from the bank 5 to present contact surfaces. From Fig. 4, it will be observed that alternate sets of contacts, such as the sets 7, have their corresponding contacts arranged in the same horizontal plane, being secured between the same two adjacent insulating layers 6. The same relation likewise holds with respect to corresponding contacts of each of the remaining sets 8, which alternate with sets 7 throughout the range of the contact bank.

But the contacts of each of the sets 8 are secured between insulating strips 6 so as to occupy a different elevation in the bank from that of corresponding contacts of each 5 of the sets 7. Briefly stated, this arrangement results in a bank construction wherein each set of contacts is vertically staggered relative to the next adjacent set. The bank 5, having thus been assembled, is made 10 secure by means of the clamping plate 9 and screws 10, and may then be mounted upon the supporting surface 2, provided therefor, as seen in Fig. 1.

Each of the mounting plates 1 of a group 15 of switches is provided with a circular aperture passing therethrough concentrically of the supporting surfaces 2, 3 and 4. These apertures form the bearings for a shaft 11 which is loosely journaled for rotation there- 20 in. Shaft 11 may be connected to some source of power so as to be constantly or periodically driven to furnish operating power for each of the switch units with which it is associated. The means whereby 25 said shaft 11 may receive its rotation from a suitable source of power, is well known in the art, and not forming any substantial part of the invention is neither shown nor described in detail. Loosely journaled upon 30 shaft 11 for both rotative and longitudinal movements relative thereto, is a spider member 14 having the radially extending arms 12 and 13. A contact structure is attached to the ends of each of the arms 12 and 13, 35 and is adapted to be rotated thereby about shaft 11 to bring the movable contacts 15, 16 and 17 into cooperative engagement with the successive sets 7 and 8 of stationary contacts in the bank 5. These movable contact structures, one of which is clearly shown 40 in Fig. 3, consists of three plates 18, 19 and 20 of conducting material having integrally projecting portions to provide respectively the movable contacts 15, 16 and 17. Plates 45 18, 19 and 20 are also each provided with a second integral portion extending downwardly as seen at 21. The said conducting plates are insulated from each other and are securely held in position by spacing pieces 50 22 of insulating material. The contact structure, when assembled in this manner, is clamped together by means of screws 23, which pass into tapped holes in arms 12 and 13 to fasten said structure thereto. The 55 upper and lower contacts 15 and 17 are offset by giving them an opposite bend so that the lateral contacting surfaces of all three contacts 15, 16 and 17 lie in the same vertical plane. The depending portions 21 of plates 18, 19 and 20 are overturned and have 60 fastened thereto, as by means of rivets, resilient wipers 24. Wipers 24 are designed to maintain a constant sliding contact with a corresponding series of conducting rings 65 25, which are mounted concentrically of

shaft 11 upon the supporting surface 3 of plate 1. A circular layer of insulation 26 serves to insulate the conducting rings 25 from the frame of the switch.

The operating power of spider 14 during 70 its rotation about shaft 11, is derived from a spiral spring 27, one end of which is fastened to the housing cup 28 and the other end to a ratchet wheel 29. The cup 28 and ratchet 29 are both arranged upon the common shaft 11 so as to be capable of rotation relative thereto, and are held in proper vertical position by collars 30 and 31, each of which are secured to shaft 11 by set screws. The collar 30 has a semi-circular notch in 80 the side thereof adapted to receive the curved end 32 of a spring 33, Fig. 2. Spring 33 is fastened to a post which is secured to the under-side of ratchet wheel 29. Said spring 33, which resiliently interconnects 85 shaft 11 and ratchet 29 by means of its engagement with the notch in collar 30, is of such force that, by clockwise rotation of the power shaft 11, the ratchet 29, to which such spring is attached, is constrained to 90 participate in a like rotation, thereby winding up the motor spring 27. When, how- ever, motor spring 27 becomes properly tensioned, its resistance against further winding 95 is sufficient to overcome the holding force of spring 33 in the notch of collar 30, and the curved end 32 of such spring 33 now slips out of said notch and rides over the surface of the constantly rotating collar 30. A spring-pressed pawl 46 holds the ratchet 100 wheel 29 from backward rotation.

The housing cup 28 under the influence of motor spring 27, is arranged to rotate spider 14 with its movable contact structures during the operation of the switch. To this 105 end, cup 28 is provided with a pair of pins 35 which extend upwardly and enter loosely into holes in lugs 36 carried by each of the arms 12 and 13. By such an arrangement the spider 14 may be moved vertically with 110 respect to shaft 11 without the pins 35 disengaging lugs 36, whereby said spider is at all times under the rotative influence of the spring-driven cup 28.

A pair of controlling magnets 37 and 38 115 are provided for each switch and are conveniently mounted upon the supporting plate 1 as shown in Fig. 1. These magnets have a common armature 39 pivoted between brackets such as 40. One end of 120 armature 39 is fork-shaped with each of the arms thereof provided with a pin 41. These pins are arranged in a slot 42 of spider 14 so that said spider is free to rotate independently of armature 39, but is forced to move 125 axially of the shaft 11 upon the armature 39 being tilted about its pivot. The other end of armature 39 is provided with notches 43 which are engaged by a roller 44 carried on the spring 45. In this manner the spring 45 130

serves to resiliently hold the armature 39 in one or the other of its operated positions, with spider 14 and its associated movable contact structures in the corresponding vertical position.

The operation of the switch is as follows: The constantly rotating shaft 11 operates, as was hereinbefore explained, to maintain the motor spring 27 in its normal or tensioned condition. The spring 27 being thus tensioned and having its inner end fastened to the ratchet 29, which ratchet is restricted from rotating by a pawl 46, exerts its force upon the housing cup 28 to which its outer end is fastened, Figs. 1 and 2. The cup 28 being urged by spring 27 to rotate, operates through the medium of pins 35 to apply a force to the spider 14, tending to rotate the same in a clockwise direction as viewed in Fig. 2. Assume that the switch at the termination of its last operation was left in the position illustrated by the switch shown in full in Fig. 1; that is, with the armature 39 tilted so as to elevate the spider 14 to its uppermost vertical position. In this case, the set of movable contacts 15, 16 and 17 carried by the arm 12 are brought into horizontal alignment with the respective contacts of a set of stationary contacts 8 occupying the higher elevation in the bank 5. This set of stationary contacts 8 with which the movable contacts 15, 16 and 17 are now in engagement, act as stop members to arrest and hold the spider 14 from further rotation under the force of motor spring 27. When the switch is again taken for use, the controlling magnet 38 is energized to attract armature 39 to its alternate position, thereby causing the spider 14 to be moved downwardly to its lower elevation. As the movable contacts 15, 16 and 17 are thus moved downwardly they pass out of horizontal alignment with the contacts of the stationary set 8, and consequently are permitted to escape therefrom to be driven forward by motor spring 27. However, in their newly assumed position, said movable contacts are now in horizontal alignment with the contacts of the next succeeding set, which, as was heretofore described, is a set 7 occupying the lower position in bank 5. The movable contacts are therefore again brought to rest by engagement with the stationary set 7. The controlling magnet 37 is now energized and spider is once more shifted to its upper position, allowing the movable contacts 15, 16 and 17 to escape and to be driven forward another step into engagement with the next stationary set 8. Controlling magnets 37 and 38 are alternately energized and de-energized, the spider 14 reciprocated axially on the shaft 11 and driven forward by motor spring 27 step by step until the movable contacts 15, 16 and 17 are brought into engagement with the proper set of stationary

contacts in bank 5, at which time magnets 37 and 38 cease to operate. During the reciprocating movement of spider 14, the wipers 24 maintain contact with conducting rings 25.

It will be observed that by providing two sets of movable contacts, each of which are adapted to coöperate with stationary contacts of the bank 5, it is only necessary to arrange said stationary contacts to cover approximately an arc of 180°. See Fig. 2. By such a provision the spider 14 upon rotating to carry a set of movable contacts out of coöperative relation to the contact bank at one extremity, simultaneously places the other set of movable contacts in working relation to the bank at its other extremity.

Considering the diagram of Fig. 5, there is shown one manner in which the above described switch may be employed as a line or distributing switch in telephone systems. In accordance with this application of the invention, each switch is individual to an incoming circuit, such as the telephone line leading from a subscriber's substation 47. By connecting the three conductors 48, 49 and 50 of the incoming line to conducting rings 25, said line is always in electrical connection with the particular set of movable contacts 15, 16 and 17 that happens to be in working relation to the stationary contact bank 5. Each of the set of stationary contacts 7 and 8 may be connected to outgoing circuits such as trunks leading to other automatic switches or to operators' positions. The subscriber at substation 47 by removing his receiver to initiate a call, closes a circuit for line relay 51 in the well known manner. Relay 51, thereupon closes the following circuit: grounded armature and contact of relay 51, 105 right-hand armature and contact of cut-off relay 52, to the conducting segment of an interrupter 53, and from here the circuit is alternately completed first to controlling magnet 37, and then to controlling magnet 110 38. Magnets 37 and 38 operate as above described, to reciprocate the contacts 15, 16 and 17, and thereby permit their step-by-step rotation into engagement successively with the stationary contact sets 7 and 8. Trunk 115 circuits that are idle are characterized by the presence of a selectable potential on the test contact thereof. As soon then as the test contact 17 encounters a stationary test contact having such a condition thereon, a 120 circuit is established for the cut-off relay 52. Relay 52 attracts its armatures and causes the deenergization of line relay 51, which in turn causes the operation of the switch to cease.

After each operation, the switch remains in its set position in readiness to extend another connection when again taken for use.

It will be obvious to others skilled in the art that many changes and alterations may 130

be made in the construction shown without departing from the spirit of the invention. For example, the movable contacts may be designed to operate constantly in the same 5 plane while the contact bank is oscillated or reciprocated in any suitable manner to accomplish the desired escapement effect.

What is claimed is:

1. In a switch, a movable contact, means 10 for driving said contact, a series of stationary contacts arranged to be engaged by said movable contact, the movement of said movable contact being arrested successively by engagement with each of said stationary 15 contacts, and reciprocating means operated to move said movable contact to disengage the same from said stationary contacts.
2. In a switch, a movable contact, means 20 for driving said contact, a series of stationary contacts arranged to be engaged by said movable contact, the movement of said movable contact being arrested successively by engagement with each of said stationary 25 contacts, and means for moving the movable contact to disengage the same from each of said stationary contacts.
3. In a switch, a movable contact, means 30 for driving said contact, a series of other contacts arranged to be engaged by said movable contact, the movement of said movable contact being arrested successively by engagement with each of the contacts of said 35 series, and a reciprocating device operated to disengage the movable contact from each of the contacts of said series.
4. In a switch, a movable contact, a motor 40 for driving said contact, a series of other contacts arranged to be engaged by said movable contact, the movement of said movable contact being arrested successively by engagement with each of the contacts of said 45 series, and electromagnetic means for imparting a reciprocating movement to said movable contact for disengaging the same from each of the contacts of said series.
5. In a switch, a movable contact, a motor 50 for driving said contact, a series of stationary contacts arranged to be engaged by said movable contact, the movement of said movable contact being arrested successively by engagement with each of said stationary 55 contacts, and electromagnetic controlling means for moving the movable contact to disengage the same from each of said stationary contacts.
6. In a switch, a movable contact, a constantly applied source of power for driving 60 said contact, a series of stationary contacts arranged to be engaged by said movable contact, the movement of said movable contact being arrested successively by engagement with each of said stationary contacts, and controlling means for moving said movable contact out of engagement with each of said 65 stationary contacts.

7. In a switch, a movable contact arranged to be driven rotatively, means for driving said contact, a series of stationary contacts arranged to be engaged by said movable contact, the movement of said contact being arrested successively by engagement with each of said stationary contacts, and means for displacing said movable contact transversely of its direction of rotation to disengage the same from each of said stationary contacts. 70

8. In a switch, movable contacts arranged to be driven rotatively, means for driving said contacts, a series of stationary contacts arranged to be engaged by said movable contacts, the movement of said movable contacts being arrested successively by engagement with each of said stationary contacts, and electromagnetic controlling mechanism for displacing said movable contacts transversely of their direction of rotation to disengage the same from each of said stationary contacts. 80

9. In a switch, a set of movable contacts arranged to be driven rotatively, means for driving said contacts, a series of stationary contacts arranged to be engaged by said set of movable contacts, the movement of said movable contacts being arrested successively by engagement with each of said stationary contacts, and means for moving said movable contact set reciprocally in a direction transverse of its direction of rotation to disengage the movable contacts from said stationary contacts. 90

10. In a switch, a movable contact arranged to be driven rotatively, a motor for driving said contact, a series of stationary contacts arranged in an arcuate bank to be engaged by said movable contact, the movement of said movable contact being arrested by engagement with each of said stationary contacts, and electromagnets for imparting a reciprocating motion to the movable contact to disengage the same from said stationary contacts. 100

11. In a switch, a series of stationary contacts, a movable contact arranged to be driven in a constant direction into engagement with each of said stationary contacts, said stationary contacts being arranged to arrest the movement of the movable contact by engagement therewith, means for imparting a reciprocating motion to said movable contact to disengage the same from said stationary contacts, and means for driving said movable contact. 110

12. In a switch, a contact bank comprising a series of sets of stationary contacts, said contact sets being arranged in groups, each group occupying a different elevation in the bank, a movable contact set, means for driving the same into engagement with said stationary contact sets, such engagement serving to arrest the movement of said mov- 120

125

130

able contact set, and means for shifting the movable contact set from one elevation to another to disengage the same from each of said sets of stationary contacts.

- 5 13. In a switch, a contact bank comprising a series of stationary contact sets, a driving shaft, a carriage mounted upon said shaft, power transmitting means inter-connecting said shaft and carriage arranged to apply a constant driving force to said carriage, a plurality of sets of movable contacts mounted on said carriage and driven thereby into engagement with said sets of
- 10 stationary contacts, the movement of said carriage being arrested successively by the engagement of the movable contact sets with each of said sets of stationary contacts, and electromagnets for reciprocating said carriage upon said shaft to disengage the movable contact sets from said sets of 20 stationary contacts.

In witness whereof, I hereunto subscribe my name this 7th day of February A. D., 1918.

EDGAR W. ADAMS.
